US0D1091918S

(12) **United States Design Patent** (10) Patent No.: **US D1,091,918 S**
(45) Date of Patent: ** Sep. 2, 2025

(54) **LAMP**

(71) Applicant: **ARTEMIDE S.p.A.**, Milan (IT)

(72) Inventor: **Mario Cucinella**, Milan (IT)

(73) Assignee: **ARTEMIDE S.p.A.** (IT)

(**) Term: **15 Years**

(21) Appl. No.: **29/818,522**

(22) Filed: **Dec. 9, 2021**

(30) **Foreign Application Priority Data**

Jun. 11, 2021 (EM) 008574768-0021
Jun. 11, 2021 (EM) 008574768-0022

CLAIM

The ornamental design for a lamp as shown and described.

DESCRIPTION

FIG. 1 is a perspective view of a lamp showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the lamp that form no part of the claimed design.

1 Claim, 7 Drawing Sheets
